UNITED STATES PATENT OFFICE.

ERNEST C. SHAW, OF MILWAUKEE, WISCONSIN, ASSIGNOR TO ALLIS-CHALMERS
MANUFACTURING COMPANY, OF MILWAUKEE, WISCONSIN, A CORPORATION OF
DELAWARE.

SETWORK.

Application filed May 10, 1926. Serial No. 107,931.

This invention relates in general to improvements in saw mill set works, and relates more specifically to improvements in the construction and operation of Trout 5 power set works of the type disclosed in Letters Patent No. 995,205, granted June 13, 1911.

An object of the invention is to provide a set works which is simple in construction 10 and efficient in operation.

In the Trout set works as disclosed in the above identified patent and as heretofore used commercially to a large extent, the column shaft which is rotatable during setting and receding operations of the knees, is connected by toothed gearing to a dial for the purpose of simultaneously rotating the latter to indicate the extent of movement of the knees. The toothed gearing 20 thus employed frequently has more or less backlash which tends to destroy the accuracy of indication by the dial.

It is an object of the present invention to provide simple and effective means for 25 maintaining accurate indication of the location of the knees by virtue of a dial operated by the column shaft, regardless of the existence of lost motion or backlash in the gearing which rotates the dial. In accordance 30 with the present improvement the dial is constantly urged about its pivotal support in the same direction by a spring or other resilient means, thereby preventing lost motion or backlash in the gearing from effecting 35 the accuracy of the indication afforded by the dial.

A clear conception of an embodiment of the invention and of the operation of apparatus constructed in accordance therewith, 40 may be had by referring to the drawing accompanying and forming a part of this specification in which like reference characters designate the same or similar parts in the various views.

Fig. 1 is a part sectional view of the upper 45 portion of the column and associated parts of an improved Trout power set works.

Fig. 2 is a top view of an improved Trout power set works.

Fig. 3 is a sectional view of the spring 50 casing for constantly urging the dial in a predetermined direction about its pivotal mounting.

The improved power set works specifically

illustrated in the drawing comprises a vertical column shaft 2 which is connected through suitable gearing and shafting to the knees mounted upon a saw mill carriage, and which is vertically supported in a stationary column 3 in a well known manner. 55 A ratchet wheel 7 is secured to the column shaft 2 directly above a gage plate 8 which is fastened to the column 3. A dial 4 is rotatably associated with the upper end of the column shaft 2 above the ratchet wheel 60 7, the dial 4 being rotatable with but at a considerably slower speed than the column shaft 2 by means of spur gears 11, 12 meshing with internal teeth 13 of the dial 4 and with the teeth of a pinion 14 secured to the column shaft 2, respectively. The ratio of these transmission gears is ordinarily such that the dial 4 makes one complete revolution for eight revolutions of the column shaft 2. The spur gears 11, 12 are pivotally 70 supported upon a stationary cross plate 5 secured to the column 3. A spring casing 15 is rotatably supported upon a pivot 20 supported by the cross plate 5, and has external teeth 16 which mesh with the internal teeth 13 of the dial 4. A coil spring 17 has its inner end secured to the hub of the casing 15 by means of a fastening 19, and the outer end of the spring 17 is permanently attached to the cross plate 5 by means of a pin 18. 80 A stationary dial pointer 9 cooperates with the graduations on the upper surface of the dial 4 and is attached to the column 3.

The periphery of the ratchet wheel 7 is provided with teeth 25 which are engageable 85 with the teeth of a pawl block 30 carried by a grip lever 21 which is pivotally supported upon the setting arm 6. The setting arm 6 is mounted to swing freely about the axis of the column shaft 2 when the pawl block 30 is released by the grip lever 21, and the arm 6 is engageable with a home stop 29 on the column 3 to positively arrest its movement, as well as the movement of the ratchet wheel 7 and of the column shaft 100 2, when the pawl block 30 is in operative position. The setting arm 6 also has a depending projection engageable with a gage latch 22. The gage latch 22 is movable about the axis of the column shaft 2 by 105 means of a gage lever 26, and has teeth adapted to interlock with peripheral teeth of the gage plate 8 and to thereby provide

a stop for limiting the movement of the setting arm 6 in a counter-clockwise direction. A pawl 24 carried by a vertical pivot 23 is engageable with the teeth 25 of the 5 ratchet wheel 7 in order to prevent recoil of the ratchet wheel after the setting arm 6 has engaged the home stop 29. The pawl 24 is operable by means of a pawl lever 10 to release the pawl 24, and is automatically 10 operable to shift the pawl into locking position by means of a pin 28 carried by the setting arm 6 which is engageable with the bumper 27 secured to the lever 10.

During normal operation of the set works, 15 the gage latch 22 is set by means of the gage lever 26 to any desired position about the gage plate 8, thus determining the limit of movement of the setting arm 6 in a counter-clockwise direction as viewed in Fig. 2. If 20 the setting arm 6 is not in engagement with the latch 22, it may first be brought into such position of engagement by releasing the pawl block 30 and shifting the arm 6 with the grip lever 21. When the power is applied 25 to set the knees forwardly, the column shaft 2 and the ratchet wheel 7 are rotated in a clockwise direction thus causing the setting arm 6 to move toward the home stop 29, by virtue of the interlock between the 30 pawl block 30 and the teeth 25. As the setting arm 6 strikes the home stop 29, motion of the column shaft in a clockwise direction is positively arrested and motion of the knees is simultaneously likewise positively stopped. Simultaneously with the 35 stopping of the column shaft 2, the pawl 24 is thrown into operative position by the pin 28, bumper 27, and lever 10, thereby preventing recoil due to the sudden stopping of the 40 column shaft 2 by the home stop 29. During rotation of the column shaft 2 while setting, the dial 4 is also moved in a clockwise direction by virtue of the gearing 11, 12, 14, but at a much slower speed. The 45 graduations on the dial 4 are such that this dial indicates the width of each board and the number of boards cut.

In order to secure subsequent setting of the knees, the grip lever 21 must first be 50 manipulated to release the pawl block 30 after which the setting arm 6 is returned to a position of engagement with the gage latch 22. Operation of the lever to throw on the power, automatically releases the 55 pawl 24 and permits subsequent setting motion of the column shaft 2. When it is desired to recede the knees, the pawl block 30 and the pawl 24 are released from the ratchet wheel 7 and the column shaft 2 is rotated in 60 counter-clockwise direction as viewed in Fig. 2 until the knees have reached the desired position.

During operation of the set works, the

spring 17 is constantly under tension, the 65 tension decreasing as the dial 4 is advanced in a clockwise direction. This tension of the spring 17 tends to urge the dial 4 in a clockwise direction at all times thereby taking up the lost motion or backlash in the 70 gears 11, 12, 14. By thus taking up the backlash, the accuracy of indication afforded by the dial 4 will always be greater, and the dial 4 is not permitted to overtravel due to backlash and thereby destroy such accuracy 75 of indication. The tension on the spring 17 is such that the pressure tending to produce rotation of the dial 4 in a predetermined direction is about two pounds when the dial 4 is at the end of its travel, and reaches a maximum of about four and a half pounds 80 at the beginning of such travel.

It should be understood that it is not desired to limit the invention to the exact details of construction and operation herein shown and described, for various modifications within the scope of the claims may occur to persons skilled in the art.

It is claimed and desired to secure by Letters Patent:

1. In a set works, a shaft, a dial rotatable 90 about the axis of said shaft, toothed gearing for intermittently transmitting rotary motion to said dial in a predetermined direction, and means for constantly urging said dial to rotate about said axis in the same 95 direction.

2. In a set works, a shaft, a dial supported by and rotatable about the axis of said shaft, toothed gearing for intermittently transmitting rotary motion from said shaft to said 100 dial in a predetermined direction, and a spring for constantly urging said dial to rotate about said axis in the same direction.

3. In a set works, a column shaft, a dial supported by and rotatable about the axis 105 of said shaft, gearing for transmitting motion from said shaft to said dial in a predetermined direction, a casing rotatable by said dial, and a spring operable by said casing to constantly urge said dial about said 110 axis in the same direction.

4. In a set works, a shaft, a pinion secured to said shaft, a dial rotatable by and about the axis of said shaft, said dial having internal teeth, gears for transmitting 115 rotary motion from said pinion to said dial through said internal teeth, a casing having external teeth engageable with said internal teeth, and a coil spring operable by said casing to constantly urge said dial to rotate 120 about the axis of said shaft in a predetermined direction.

In testimony whereof, the signature of the inventor is affixed hereto.

ERNEST C. SHAW.
